UNITED STATES PATENT OFFICE.

GUY H. CHRISTY, OF SANTA CRUZ, CALIFORNIA, ASSIGNOR OF TWO-FIFTHS TO OLIVER BOYEA, OF SANTA CRUZ, CALIFORNIA.

MAIL-BAG RECEIVER.

1,127,732.

Specification of Letters Patent. Patented Feb. 9, 1915.

Application filed March 23, 1914. Serial No. 828,522.

To all whom it may concern:

Be it known that I, GUY H. CHRISTY, a citizen of the United States, residing at Santa Cruz, in the county of Santa Cruz and State of California, have invented new and useful Improvements in Mail-Bag Receivers, of which the following is a specification.

This invention relates to apparatus for receiving mail bags, or other parcels, from moving vehicles or trains.

It is one of the objects of the present invention to provide an apparatus of great strength and rigidity for receiving mail bags and other parcels, which it may be desired to deposit at a station, from a moving vehicle, such as a railway mail car.

A further object of the invention is to provide a mail bag receiving apparatus, including a stationary support, upon which is mounted a tiltable cantaliver, having a carriage carrying hanger arms or a crane structure, and upon the latter is supported a collapsible basket which is designed to directly receive the parcel to be deposited, said apparatus being capable as a whole for adjustment to extended or receiving position and collapsible in inoperative position for occupancy of small space when not in actual use.

The invention consists of a stationary tower or stanchion structure, upon which is pivoted a tilting cantaliver, with means for controlling the tilting of the same, and locking means therefor.

It further consists of a foldable basket or receiving device which is slidably and hingedly related to the cantaliver so as to be projectable to receiving position adjacent to the side of a railway mail car, and which is collapsible for folding into unused position so as to economize in space and be protected against injury by collision with vehicles moving about the tower.

Having reference to the accompanying drawings—Figure 1 is a plan view of the apparatus, with the receiving basket adjusted and unfolded to receiving position. Fig. 2 is a side elevation of the apparatus shown in connection with a mail bag releasing device on a car. Fig. 3 is a side eleva-

tion of the apparatus in its telescoped and collapsed position, with the basket closed. Fig. 4 is a rear elevation of the stanchions and slide, showing the locking devices of the cantaliver.

In the drawings, 2 represents a stationary stanchion or tower structure which may be suitably braced, and upon the upper end of which is mounted, upon pivots 3, a tiltable cantaliver 4 comprising parallel side members forming guideways for a slideable or telescopic carriage 5. The parallel side members of the carriage 5 rest upon the adjacent slides of the cantaliver 4 and are transversely braced, as at 6.

The cantaliver structure 4 includes arcuate braces 7, one on each side of the stanchions or tower, which are perforated at 8, Fig. 4, for the reception of latch pins 9 adapted to be projected through the tower structure standards by suitable springs 10. The pins 9 operate to lock the cantaliver 4 in the horizontal position shown in Figs. 1, 2 and 4, and when the pins are withdrawn from the braces 7 of the cantaliver, by a pull on releasing lanyards 11, the cantaliver is released and may tilt to the closed oblique position, Fig. 3. The lanyards 11 may be released, as desired, and temporarily fastened over cleats or projections 12 provided for that purpose on the standards of the tower.

When in the horizontal position, as in Figs. 1 and 2, the carriage 5 is projected forwardly and locked against sliding movement upon the cantaliver 4 by snap pins 13 which are connected to springs 14, one on each side of the carriage members. These pins are adapted to snap into forward or rear sets of apertures 15 provided for their reception in the cantaliver members. When it is desired to telescope the slide or carrier 5 in the cantaliver 4, the operator retracts the locking pins 13 by pulling on a releasing flexible connection 16, which is connected to the latch pins 18, and upon the withdrawal of these from the forward holes 15 the carriage 5 may be pushed rearwardly along the ways of the cantaliver 4 to the position shown in Fig. 8.

Upon the carrier 5 there is pivoted at 17

a pair of parallel arms forming a crane 18. The crane 18 carries upon its lower end an adjustable bracket structure 19, provided with a multiplicity of holes 20 which permit 5 of the various adjustments of the bracket 19, as to the crane arm 18, which parts are secured together by bolts or other suitable means 21, Fig. 2. The bracket 19 includes a pair of upwardly extending, slotted bearings 22, Figs. 1 and 2; these slotted bearings being provided with numerous perforations 23 for the reception of fastening screws 24. These screws 24 project through a horizontal supporting bar 25 which is slotted, as at 10 26, to receive the screws 24, the slots allowing longitudinal movement of the supporting bar 25 as to the bearing members 22 of the bracket 19, and which supporting bar is shiftable from end to end of the slotted bearing members 22 as may be desired under 15 diverse conditions. Upon the outermost ends of the supporting horizontal bar 25 are adjustably mounted slotted arms 27, Figs. 2 and 3, the slots of which permit the longitudinal shifting of the arms 27 upon the support 25.

In Fig. 2 the arms 27 are shown as shifted downwardly upon the horizontal bar 25 and pinned thereto by removable keys 28; while 30 in Fig. 3 the arms 27 have been shifted upwardly, as to the horizontal support 25, for the purpose of permitting the cantaliver 4 and the crane members 18 to be swung down toward the ground to folded position.

The arms 27, of which there is one at each end of the horizontal supporting bar 25, are attached to one slatted side 29 of a basket structure which consists also of an opposite foldable slatted side 30; the sides 29 and 30 35 being pivotally or hingedly connected, as at 31, Figs. 1 and 2. The basket sides 29 and 30 are locked in the open position by knuckle-jointed links 32 and 33 which are jointed together at 34 and pivoted at their 40 outer respective ends to the basket sides 30 and 29. When it is desired to close or fold the basket sides together, the knuckle-jointed link structures are folded about their pivots 34 and swung together in the position, as indicated in Fig. 3, in which the basket is shown as closed.

In operation, when it is desired to position the basket so as to receive mail bags, or other parcels, from a moving railway car, 55 the operator swings the cantaliver 4 to the horizontal position shown in Fig. 2 by pulling upon a hoisting flexible member 4', which is connected in this case to one of the transverse braces 6 of the carriage 5, and 60 which is assumed to be in its telescoped position, as shown in Fig. 3. As the cantaliver swings to a horizontal position the snap bolts 9 spring into their respective keeper apertures 8 in the curved brackets 7 and the 65 cantaliver is then locked in a horizontal posi-

tion. Thereafter the operator pulls on the latch-releasing lanyard 16 to withdraw the carriage locking pins 13, whereupon the carriage will slide forwardly horizontally along the ways of the cantaliver 4 into the position shown in Fig. 1 and the crane 18 will swing to its supporting position, being engaged and suspended therein by supporting lugs 18' on the carriage 5. Having projected the carriage 5, the operator then proceeds to adjust the basket arms 27 from their retracted position on the supporting bar 25 to the projected position, Fig. 2, and may then unfold the basket to its open position to receive the mail bags, or other parcels, indicated at A, Fig. 2.

The present apparatus is designed to cooperate with a mail bag casting-off device, which is indicated generally at B, Fig. 2, and which includes a lever 40 of a crank-shaft 41, to the crank of which is connected an oscillating lever 42, which, when tilted, rocks a rocker shaft 43 on the cast-off device B and releases the bags, or other parcels A, in a position over the basket 30. 90 This release of the bags is accomplished during the motion of the train when the lever 40 encounters a striking pin or abutment 44, adjustably secured to the carriage 5 and projecting in the path of the arm 40. 95 After the cast-off device has been actuated by the striker 34 to release the parcel A, which drops into the basket 30 positioned therefor, then the operator may collect the parcels or mail bags from the basket and 100 immediately, if desired, proceed to fold the basket into closed position, shift the basket-carrying arms 27 to compact position on the crane 18, unlock the carriage 5 by withdrawing the pins 13 from the cantaliver 4, and 105 telescope the carriage. Then by pulling on the releasing lanyards 11 of the cantaliver locking pins 9 the cantaliver may tilt downwardly.

In order that the cantaliver will not fall 110 violently when released by the operator, the controlling flexible member 4' thereof may be temporarily latched over a cleat or retaining dog 4" secured on a convenient portion of the tower. The operating member 4' 115 will serve to sustain the cantaliver 4 in its unlocked position and against its tilting until the operator can release the controlling member 4' from the cleat 4" and gradually lower the cantaliver 4 with its associated members.

Having thus described my invention, what I claim and desire to secure by Letters Patent is—

1. A mail bag receiving apparatus, comprising a stationary tower or support, a basket for receiving the mail bags, a cantaliver mounted upon said support, and means connecting the basket to the cantaliver so 130

- that the basket may slide while the cantaliver remains stationary for carrying the basket to a receiving position in proximity to the mail delivering device of a moving vehicle and whereby the basket may be retracted to a compact position when not in use.
2. In combination with a support, a cantaliver pivoted thereon and movable from a vertical to a horizontal position and vice versa, a carrier on the cantaliver movable independently of the latter from retracted to projected position and vice versa, and a receiver connected to the carrier.
3. The combination in a mail or parcel receiving apparatus, of a standard or tower, a cantaliver pivoted thereon and means carried by the cantaliver for slidably and bodily carrying a basket into and from a usable projected mail-receiving position.
4. In combination with a support and a cantaliver pivoted thereon, a carrier movable on the cantaliver and independently thereof, a crane pivoted to the carrier, a receiver, and means movably connected to the crane and to the receiver whereby when the cantaliver and crane assume vertical position the crane will move relative to the receiver to allow the latter to be moved to a vertical position adjacent to the support.
5. In combination with a support and a member thereon movable to a horizontal and vertical position, a carrier slidable on the member, a receiver, and means connecting the receiver and carrier whereby when the member is moved to horizontal position the carrier may be projected and the receiver moved to receiving position and whereby when the member is moved to vertical position the carrier may be retracted and the receiver moved to collapsed position adjacent to the support.
6. In a mail bag receiving apparatus, the combination with a stationary support, of a cantaliver tiltable thereon, a parcel receiver, and a carrier slidably mounted on said cantaliver to which said receiver is connected and whereby the same is movable to and from a receiving position, said carrier including a crane having slotted bearings to which said receiver is adjustably connected.
7. In a mail bag receiving apparatus, the combination with a stationary support, of a cantaliver tiltable thereon, a parcel receiver, and a carrier mounted on said cantaliver to which said receiver is connected and whereby the same is movable to and from a receiving position, said carrier including a crane having slotted bearings to which said receiver is adjustably connected.
8. In a mail bag receiving apparatus, the combination with a stationary support, of a cantaliver tiltable thereon, a parcel receiver, and a carrier mounted on said cantaliver to which said receiver is connected and whereby the same is movable to and from a receiving position, said carrier including a crane having slotted adjustable bearings to which said receiver is adjustably connected.
9. In a mail receiving apparatus, the combination with a stationary support, of a cantaliver pivoted on the support, a foldable receiver and means slidably mounted on the cantaliver for carrying the receiver to and from a receiving position.
10. In a mail receiving apparatus, the combination with a stationary support, of a cantaliver, and a foldable receiver connected thereto with means slidably mounted on the cantaliver for carrying the receiver to and from a receiving position, said means being provided with devices for permitting the adjustment of the receiver to different heights.
11. In a mail or parcel receiving apparatus, the combination of a parcel-receiving basket, a stationary support, a cantaliver pivoted upon said support, means for swinging the cantaliver to a horizontal position, means for locking the same in a horizontal position, a carrier slidably mounted upon the cantaliver, and a supporting crank pivotally connected to the carrier, said crane, carrier and cantaliver co-operating to carry the receiver to a projected position for receiving parcels and to a collapsed and contracted position when not in use.
12. In an apparatus for receiving parcels from a movable vehicle, a stationary tower or support, a cantaliver adjustably mounted thereon for movement to a horizontal position, means for locking the same in a horizontal position, a carrier slidably mounted upon the cantaliver, and means for locking the carrier in the several positions on the cantaliver.
13. An apparatus for receiving parcels from a movable vehicle, comprising a stationary support, a cantaliver pivotally mounted upon said support and carrying a parcel receiver, snap locks automatically operative to latch the cantaliver in a predetermined position upon the support, means for operating the locks to release the cantaliver, and a device connected to the cantaliver and connectable to a part of said support so as to temporarily hold the cantaliver against swinging motion when said locks are released.
14. In combination with a support and a member movably mounted thereon and means to connect the support and member to allow the member to move to vertical and horizontal positions, a receiver, and means connected to the receiver and to the member whereby when the member is moved to horizontal position the receiver may be moved to horizontal position and then slid or projected out from the support and whereby when said member is moved to a vertical position the receiver may be retracted and then moved so as to occupy collapsed vertical position adjacent to the support.

15. In combination with a support and a track member pivoted to the support so as to be movable from a horizontal to a vertical position, a receiver, and means slidable on said track member to support the receiver.
16. In combination with a support and a track member pivoted to the support so as to be movable from a horizontal to a vertical position, a receiver, and means slidable on said track member to support the receiver, said receiver when the member occupies vertical position being slidable inwardly into collapsed position and when the member is moved to horizontal position being slidable outwardly to receiving position.
17. In combination with a support and a member pivoted thereto, a carriage slidable on the support, a receiver, means to pivotally connect the receiver to the carriage, and means to connect the receiver to said pivoting means whereby the receiver may be moved relative to the pivoting means to occupy collapsed position.
18. In combination with a support and a pivoted member thereon having a track, a carriage slidable on the track, a receiver, and

a crane connected to the receiver and carriage.

19. In combination with a support and a pivoted member thereon having a track, a carriage slidable on the track, a receiver, a crane pivoted to the carriage and movable to a vertical position to extend adjacent to the support, and means to movably connect the receiver to the crane whereby the receiver may be collapsed against the support.

20. In combination with a vertical support and a pivoted member thereon having a track, a carriage on the track, a crane pivoted to the carriage and movable to a position to align with and extend on opposite sides of the support, and a receiver connected to the crane and movable to a vertical position against the support.

In testimony whereof I have hereunto set my hand in the presence of two subscribing witnesses.

GUY H. CHRISTY.
